UNITED STATES PATENT OFFICE.

TAKEO TERAGAWA, OF LOS ANGELES, CALIFORNIA.

DENTAL VIBRATORY MATRIX.

Application filed December 6, 1926. Serial No. 152,931.

This invention relates to improvements in matrix devices for use in dentistry, and its objects are to simplify porcelain technology in dentistry, and to expedite the process pertaining thereto.

Other objects are to avoid dismembering the porcelain tip or saddle before it is subjected to the baking process, to produce on the porcelain tip, a smooth and sharp-angled shelf for the drawing of a perfect wax pattern in making gold backings, to provide means for vibrating the matrix whereby the porcelain powder is better lubricated and more quickly condensed, and to provide improved clamp elements for the matrix, whereby the tip or saddle is held in perfect adjustment in the desired position, and the engaging and disengaging of the porcelain facings is simplified.

Another object is to provide a vibratory matrix embodying simplicity, efficiency, reasonable cost of production, and ease of operation without skilled knowledge on the part of the instructed.

Other objects and advantages may appear in the subjoined detail description.

In the drawings, Figure 1 is a side elevation of a vibratory dental matrix embodying the features of the present invention. Fig. 2 is a top plan view of the dental matrix. Fig. 3 is a fragmentary and sectional view of the handle, showing the vibratory elements. Fig. 4 is a detail view of the vibratory spring. Fig. 5 is a fragmentary and enlarged view of the device with parts in section, and showing the device in use.

Referring to the drawings, the top plate member 11, is of a circular form, and has therein, the apertures 12, each adapted to receive a tooth form 13. The cover 14, has similar apertures. The main plate member 11 is secured to the handle shank 15, and is further provided with depending flanges 16. The cover 14, serves as a holding member for the tooth forms, and is pivotally secured to the handle by a retaining nut 17 and washer 18.

The holding elements relative to each aperture, are substantially duplicates, and a description of one set of holding elements will suffice. Each set of holding elements consists of a movable jaw member 19, having integral supporting rods 20, which pass through a depending flange 16. A plate 21, connecting the extremities of rods 20, may be pressed by the operator to move jaw mem-

ber 19 to its release position, and springs 22, interposed between plate 21 and flange 16, serve to actuate the movable jaw to operative position.

The handle shank 15 has mounted therein, a toothed wheel 23. A vibratory spring 24, extends in slot 28 in shank 15, and has a series of adjustment holes 26. A screw 27, serves to bind the spring 24 in an operative position relative to wheel 23. The handle 28, is secured by a screw 29, to shank 15, and may be adjusted to and from the operative parts. The vibratory spring will, when the toothed wheel is rotated, produce vibrations in all parts of the holding elements, thereby settling and condensing the porcelain powder quickly in the processes for which the matrix is intended. It may be noted that aperture 12, has a notch 30, adapted to receive a longer tooth, or to hold the tooth in a different position. The holder or cover 14, when the tooth form is to be removed from the matrix, may be rotated backwardly, thereby leaving a straight edge on the tooth, whereby the same may be readily removed.

In use, the tooth form is supported as shown in Fig. 5, for the ceramic processes involved, and, through the vibratory mechanism, the processes are hastened, thereby saving time, and the holding elements tend to form perfect abutment edges for facings and backings.

What is claimed is:

1. In a dental matrix of the character set forth, a plate member having two apertures therein, depending flange portions adjacent to each aperture, a movable jaw mounted in opposed relation to each depending flange portion, springs normally urging the movable jaws to operative position, a cover mounted in the top of the plate member and having apertures to correspond with the apertures in the plate member, a handle for the plate member, and manually actuated vibratory elements mounted in the handle.

2. In a dental matrix of the character set forth, a plate member and a cover for the plate member, each of circular form and each having corresponding apertures therein, depending flange portions adjacent to the apertures in the plate member and integral with the plate member, a movable jaw mounted in opposed relation to each depending flange portion, a spring normally urging each movable jaw to operative position, a handle for the plate member, said plate mem-

ber and cover being co-axially arranged relative to the handle, and manually actuated vibratory elements mounted in the handle.

3. In a dental matrix of the character set
5 forth, the combination with two substantially circular members, each having two apertures therein, and one mounted above the other, the upper member being independently rotatable relative to the lower member,
10 of depending flange portions on the lower

member and adjacent to the apertures therein, a movable and spring-actuated jaw mounted in opposed relation to each depending flange portion, a handle axially arranged relative to and supporting the circular members, and manually actuated vibratory elements in the handle. 15

In testimony whereof, I hereunto affix my signature.

TAKEO TERAGAWA.
